CLAIM

The ornamental design for a multiple panel connector, as shown.

DESCRIPTION

FIG. 1 is a perspective view of a multiple panel connector showing my new design;

FIG. 2 is a top plan view;

FIG. 3 is a front elevational view;

FIG. 4 is a side elevational view taken facing a recess; and

FIG. 5 is a bottom plan view;

FIG. 6 is a perspective view of an alternate embodiment.

FIG. 1

FIG. 2

FIG. 3

FIG. 4

FIG. 5
